VENTILATION CONTROL MECHANISM

Henry D. Breen, Chicago, Ill., assignor to Union
Asbestos & Rubber Company, Chicago, Ill., a
corporation of Illinois

Application July 13, 1948, Serial No. 38,365

7 Claims. (Cl. 98—6)

1

My invention relates to a ventilating control mechanism and in particular to a ventilating control mechanism suitable for use in refrigerated railroad cars in which the ventilating apparatus is driven from a take-off wheel in driving engagement with a car-supporting wheel.

In freight cars of the refrigerated type, the car body defines a freight-carrying chamber and a coolant chamber. The latter chamber is filled with ice or other coolant, and air circulation thereover and through the freight-carrying chamber causes the freight to partake of the temperature of the coolant, thus preventing spoilage. A wheel-driven fan is positioned between the chambers to force air circulation therebetween when the car is moving. In addition, auxiliary air passages and dampers are provided to define independent paths for air flow between the chambers to permit air circulation by natural convection and to facilitate air flow through the hatchways to the cargo. These dampers must be closed during fan operation to achieve effective fan action.

Circumstances may dictate the operation of the refrigerated car in any one of several conditions. If the car is travelling, the take-off wheel may be engaged with the car supporting wheels to cause fan operation, in which case the dampers should be closed for most effective fan operation. However, if it is not desired to operate the fan, the dampers should be opened and the take-off wheel retracted to a spaced position relative to the car supporting wheels. On the other hand if the car is stationary, it may be desirable to operate the fan from an auxiliary precooling drive mechanism, in which case the take-off wheel should be spaced from the car supporting wheels and positioned to receive the pre-cooling drive mechanism and the dampers should be closed. However, if it is not desired to operate the fan with the car stationary, dampers should be open to achieve a maximum degree of convection air flow.

In accordance with the present invention, the power take-off wheel mechanism and the damper control mechanism are connected to a common swingable control arm. This arm is provided with indexing mechanism to sustain it in either of three selected positions, one position corresponding to fan operation under the wheel drive and with the dampers closed, a second position corresponding to fan operation under auxiliary drive with the dampers closed, and the third position corresponding to the dampers open but no fan operation for natural ventilation. The control arm is placed in a position readily accessible from the ground where it may readily be operated in accord with conditions.

It is, therefore, a general object of the present invention to provide an improved mechanism for blocking off or closing the auxiliary air passages about the fan of a refrigerated railroad car dur-

2

ing fan operation and to open these passages when the fan is not operating.

Further, it is an object of the present invention to provide an improved mechanism for selectively controlling the wheel-driven fan and the dampers of a railroad car and which incorporates a single operating arm movable to predetermined positions to achieve the desired operation.

Another object of the present invention is to provide an improved ventilation control mechanism for a railroad car which is readily accessible from the ground and which provides complete control of ventilation.

Still another object of the present invention is to provide an improved mechanism selectively to engage a take-off wheel against the surface of a car-supporting wheel.

My invention further resides in features of construction, combination, and arrangement whereby an improved ventilator which is simple in construction and reliable in operation is achieved and which does not interfere with other portions of the car structure.

The novel features which I believe to be characteristic of my invention are set forth with particularity in the appended claims. My invention, itself, however, both as to its organization and method of operation, together with further objects and advantages thereof, may best be understood by reference to the following description taken in connection with the accompanying drawing in which:

Figure 1 is an end elevational view of a refrigerated freight car incorporating the features of the present invention and with parts broken away to show more clearly the construction thereof;

Figure 2 is a fragmentary side elevational view of the car of Figure 1 with portions in cross section to show more clearly the construction thereof;

Figure 3 is a fragmentary cross sectional view through the axis III—III, Figure 1, with parts in elevation; and

Figure 4 is a fragmentary isometric view showing the ventilating control structure of the present invention.

As shown in Figures 1 and 2, the refrigerated railroad car comprises a body B supported by trucks T. The trucks T include carriage portions 14 which are swingable relative to the center beam 108 on body portion B. Each truck includes a plurality of axles 12 and a plurality of rail-engaging wheels 10. The wheels are of conventional flanged construction having tapered rail engaging surfaces with outwardly extending flanges at their inner sides. The car body B rests on the carriage 16 which is supported by the center beam 108 which rests on the truck T. The body B is divided by baffle 38, Figure 2,

into a freight or load carrying chamber 22 and a coolant chamber 20. A door 24 provides access to the latter chamber.

An ice-supporting grate 26 is positioned at the lower part of the coolant chamber 20 and is in mating engagement with the vertical inner walls 28 and 30. These walls are of perforated material and act to retain the ice 32 in spaced relationship with the end of the body B and the baffle 38, thereby preventing obstruction of cooling air flow by the ice itself. A swingably supported grate 34 is mounted intermediate the length of wall 30 and swings downwardly to engage the stop 36 when it is desired to provide ice only in the upper half of the coolant chamber 20. The baffle 38 defines an opening 40 at its lower portion to permit air flow from the coolant chamber 20 to the freight chamber 22. At its upper portion, the baffle 38 receives the dampers 42. Each of the dampers blocks off or closes the corresponding opening 43 provided in baffle 38. As shown best in Figures 2 and 3, a housing 46 is mounted over the centrally disposed opening 45 in the upper portion of baffle 38. This housing defines an air passage in which the fan assembly 48 is disposed and terminates in the louvers 44.

Louvers 50 extend across wall 28 in the region opposite housing 46.

The fan assembly 48 operates when rotated to draw air from the freight chamber 22 through the opening 40 in baffle 38 into the coolant chamber 20. The air then travels in the direction generally indicated by arrows 52 over the ice 32, thereby being cooled. The air then flows through the louvers 50 and 44 into the freight chamber 22.

As best shown in Figure 1, the dampers 42 are attached to a common shaft 54 which, in turn, is supported from the wall 38 by brackets 56. The vertically extending damper pull rod 58 is attached to the dampers by the crank arm 60 which acts to swing the dampers to the open position when the pull rod 58 is shifted downwardly. As shown best in Figure 1, a sleeve 61 extends through the floor 18 to receive the damper pull rod 58. The damper pull rod 58 is biased in the upward direction by the compression spring 62 which bottoms at its lower end against the washer 64 and at its upper end against the washer 66. The latter washer is held against axial shifting movements along the pull rod 58 by the cotter pin 68.

Inasmuch as the spring 62 biases the pull rod 58 in the upward direction, the dampers 42 are normally closed.

As best shown in Figure 3, the fan assembly 48 includes a bearing housing 70 which is in threaded engagement with the support sleeve 72, as shown at 74. The support sleeve 72 has flange portions which are supported from the baffle 38 by the bolts 75 or other suitable devices. The fan assembly 48 includes a fan blade portion 72 supported by a shaft 78 which, in turn, is held by bearings 80. These bearings are received in the housing 70 and are fixedly supported thereby. The bevel gear 82 is also supported on the shaft 78 at a point intermediate the bearings 80.

The bevel gear 84 is mounted for rotation about a vertical axis and is in mating engagement with the bevel gear 82, being held in that position by the bearing 86 which is received in the support sleeve 72.

The bevel gear 84 is attached to the flexible shaft 90 which is received in the flexible tubular housing 88. As best shown in Figure 1, this hous-

ing extends downwardly through the floor 18 of the car B to the carriage 92.

The carriage 92 supports a bearing 94, Figure 4, which receives the shaft 90. The rubber-tired take-off wheel 91 is mounted on the shaft 90 in the region the latter extends beyond bearing 94. Hence, as the take-off wheel 91 is rotated, the fan 76 is likewise rotated.

The carriage 92 is supported from the hinge butt 104, Figure 4, by the end member 93. The latter member extends upwardly from carriage 92 and is provided with an overhanging lip which encircles the pin 106 to define a swingable support. A horizontal rod 96 is received in opening 102 in the end wall 93. The carriage 92 is biased to a predetermined position relative to rod 96 by the compression spring 100 which bottoms at one end against the washer 98 and at the other end against the wall 93. This spring serves to maintain pressure of the wheel 91 against the car wheel 10 to provide a snug driving engagement.

As best seen in Figures 2 and 4, the carriage 92 is of channel-shaped cross section and has side sections 95 which cooperate with an under section 97 to define a solid and rigid body.

The rod 96 is fixedly attached to the bracket 104 which, in turn, is swingably supported from the center beam 108 by pin 106, Figure 1.

The rod 96 and the limit of motion of the carriage 92 are so fixed relative to one of the wheels 10 that when the carriage 92 is in the free or released position, the wheel 91 rides against the surface of the support wheel 10.

It is the function of the operating mechanism shown generally at 110 selectively to control the fan 48 and the dampers 42. This mechanism comprises a U-shaped bar swingably supported from the plate 117 which is welded or otherwise attached to the under carriage 116 of car body B. The mechanism 110 is supported by the pin 116 which is received in the arm portion 112 thereof. The mechanism 110 further includes a horizontally extending operating handle portion 114.

A locking pin 124 is received in suitable openings in the opposite leg portions of the U-shaped control mechanism 110 and may be received in either of the indexing openings 118, 120, or 122 in accord with the position of the operating

mechanism 110. A compression spring 126 surrounds the pin 124 and bottoms against the washer 128 to urge the locking pin 124 toward the indexing openings. The washer 128 is held against axial movement relative to the pin 124

by a cotter pin or similar device (not shown). An adjusting knob 130 is supported on the end of a pin 124 to enable the bias of spring 126 to be overcome to retract pin 124 from the indexing openings and permit the operating handle 114 to be swung to shift the position of the mechanism to align the locking pin 124 with a selected indexing opening.

A lengthy horizontal pin 134 is fixedly attached to the arm 112 at a point intermediate the pin 116 and the locking pin 124 to define a lost motion connection between arm 112 and arm 136. The arm 132 is pivotally supported by a pin 134 and, in addition, is pivotally attached to one of the side portions 95 of the carriage 92 by pin 97. Arm 132 is provided with an elongated hole to receive pin 97 to free that arm from the ordinary up and down movements of the carriage 92 under road operation.

The arm 132 is of such length and the pin 116 is so positioned relative to the carriage that when

the operating mechanism 110 is vertically disposed, as shown in the solid lines of Figure 1, the carriage 92 is released and the take-off wheel 91 rides against support wheel 10 to drive the fan 48. However, when the operating mechanism 110 is swung to the position corresponding to the indexing openings 120 and 122, the carriage 92 is shifted against the bias of spring 100 and tilted upwardly, as shown in the dotted lines in Figure 1, to move the take-off wheel 91 to a spaced position relative to the support wheel 10, thereby discontinuing the fan drive.

A U-shaped stationary bracket 140 is supported from the pin 116 and at its outer portion supports the pin 138. The latter pin pivotally supports the damper operating lever 136 which is pivotally attached to the forked end portion 142 of the damper pull rod 58 by the pin 144. The damper operating lever 136 extends a distance beyond the pin 138 sufficient to engage the lengthy pin 134 as the control mechanism 110 is swung beyond the position corresponding to indexing opening 120, thereby causing the lever 136 to be swung to shift rod 58 against the bias of spring 62 when the mechanism 110 is swung to a position corresponding to indexing opening 122.

The take-off wheel 91 is preferably provided with a tire of rubber or similar material having a high coefficient of friction against the surface of the steel support wheel 10. Moreover, this wheel is of relatively small diameter, such as, for example, eight inches, to impart relatively high velocity rotations to the fan 48 as the car travels.

From the foregoing description, it will be evident that the mechanism of the present invention provides a simple unitary structure which may be swung to any one of three positions and thereby controls the operation of the ventilating system of the car. In one position, that corresponding to indexing opening 118, Figure 4, the fan 48 is energized and forced air ventilation is provided between the coolant chamber 20 and the freight chamber 22. In the second position, that corresponding to indexing opening 120, the wheel 91 is swung free of the car wheel to receive the drive elements of precooling mechanism. In addition, the dampers 42 remain in the closed position. Finally, in the position corresponding to indexing opening 122, where the arm 112 is swung beyond the position corresponding to indexing opening 120, no mechanical energy is applied to fan 48 but the shutters 42 are swung to the open position. In this case, free air flow takes place between the coolant chamber 20 and the freight chamber 22.

Moreover, it will be apparent that the apparatus of the present invention provides a readily accessible operating handle 114 disposed on one side of the car where it may be reached from the ground. This handle is locked in position but may be conveniently released for purposes of adjustment. It is thus possible to adjust the ventilating system of the car in a simple and convenient manner.

In the appended claims I have used the term "operating rod" to refer to the rod 58 which operates the dampers in accord with its position. I have also used the words "control arm" to refer to arm 112 which is swingably attached to the car body. The words "operating lever" refer to the lever 136, Figure 4, which is pivotally attached to the car body and the operating rod 58.

While I have shown a particular embodiment of my invention, it will, of course, be understood

that I do not wish to be limited thereto since many modifications both in the parts themselves and their cooperative structure may be made without departing from the spirit and scope of my invention. I, of course, contemplate by the appended claims to cover any such modifications as fall within the true spirit and scope of my invention.

What is claimed is:

10. A mechanism for selectively engaging a take-off wheel against the surface of a car wheel supporting a car body comprising a rod supported in fixed horizontal position by the car body, a carriage supporting said take-off wheel and having an opening to receive said rod, spring means biasing said carriage relative to said rod to engage said take-off wheel and said car wheel, a control arm swingably supported from said car body for movements about a horizontal axis, and an arm pivotally attached to said carriage and pivotally attached to said control arm to overcome the bias of said spring means and move said take-off wheel to a spaced position relative to said car wheel.
15. A mechanism for selectively engaging a take-off wheel against the surface of a car wheel supporting a car body comprising a rod supported in fixed horizontal position by the car body, a carriage supporting said take-off wheel and having an opening to receive said rod, spring means biasing said carriage relative to said rod to engage said take-off wheel and said car wheel, a control arm swingably supported from said car body for movements about a horizontal axis, and an arm pivotally attached to said carriage and pivotally attached to said control arm to overcome the bias of said spring means and move said take-off wheel to a spaced position relative to said car wheel.
20. A mechanism for selectively engaging a take-off wheel against the surface of a car wheel supporting a car body and to move an operating rod relative to said body, said mechanism comprising a movable carriage supporting said take-off wheel, means biasing said carriage to align said take-off wheel and said car wheel for driving engagements, a control arm swingably attached to said car body and operative to engage said operating rod when swung beyond a predetermined position, and means interconnecting said control arm and said carriage to overcome the bias of said first means at a position short of said predetermined position to move said take-off wheel to a spaced position relative to said car wheel prior to engagement of said operating rod and said control arm.
25. A mechanism for selectively engaging a take-off wheel against the surface of a car wheel supporting a car body and to move an operating rod relative to said body, said mechanism comprising a movable carriage supporting said take-off wheel, means biasing said carriage to align said take-off wheel and said car wheel for driving engagements, a control arm swingably attached to said car body and operative to engage said operating rod when swung beyond a predetermined position, and means interconnecting said control arm and said carriage to overcome the bias of said first means at a position short of said predetermined position to move said take-off wheel to a spaced position relative to said car wheel prior to engagement of said operating rod and said control arm.
30. A mechanism for selectively engaging a take-off wheel against the surface of a car wheel supporting a car body and to move an operating rod relative to said body, said mechanism comprising a movable carriage supporting said take-off wheel, means biasing said carriage to align said take-off wheel and said car wheel for driving engagements, a control arm swingably attached to said car body and operative to engage said operating rod when swung beyond a predetermined position, and means interconnecting said control arm and said carriage to overcome the bias of said first means at a position short of said predetermined position to move said take-off wheel to a spaced position relative to said car wheel prior to engagement of said operating rod and said control arm.
35. A mechanism for selectively engaging a take-off wheel against the surface of a car wheel supporting a car body and to move an operating rod relative to said body, said mechanism comprising a movable carriage supporting said take-off wheel, means biasing said carriage to align said take-off wheel and said car wheel for driving engagements, a control arm swingably attached to said car body and operative to engage said operating rod when swung beyond a predetermined position, and means interconnecting said control arm and said carriage to overcome the bias of said first means at a position short of said predetermined position to move said take-off wheel to a spaced position relative to said car wheel prior to engagement of said operating rod and said control arm.
40. A mechanism for selectively engaging a take-off wheel against the surface of a car wheel supporting a car body and to move an operating rod relative to said body, said mechanism comprising a movable carriage supporting said take-off wheel, means biasing said carriage to align said take-off wheel and said car wheel for driving engagements, a control arm swingably attached to said car body and operative to engage said operating rod when swung beyond a predetermined position, and means interconnecting said control arm and said carriage to overcome the bias of said first means at a position short of said predetermined position to move said take-off wheel to a spaced position relative to said car wheel prior to engagement of said operating rod and said control arm.
45. A mechanism for selectively engaging a take-off wheel against the surface of a car wheel supporting a car body and to move an operating rod relative to said body, said mechanism comprising a movable carriage supporting said take-off wheel, means biasing said carriage to align said take-off wheel and said car wheel for driving engagements, a control arm swingably attached to said car body and operative to engage said operating rod when swung beyond a predetermined position, and means interconnecting said control arm and said carriage to overcome the bias of said first means at a position short of said predetermined position to move said take-off wheel to a spaced position relative to said car wheel prior to engagement of said operating rod and said control arm.
50. A mechanism for selectively engaging a take-off wheel against the surface of a car wheel supporting a car body and to move an operating rod relative to said body, said mechanism comprising a movable carriage supporting said take-off wheel, means biasing said carriage to align said take-off wheel and said car wheel for driving engagements, a control arm swingably attached to said car body and operative to engage said operating rod when swung beyond a predetermined position, and means interconnecting said control arm and said carriage to overcome the bias of said first means at a position short of said predetermined position to move said take-off wheel to a spaced position relative to said car wheel prior to engagement of said operating rod and said control arm.
55. A mechanism for selectively engaging a take-off wheel against the surface of a car wheel supporting a car body and to move an operating rod relative to said body, said mechanism comprising a movable carriage supporting said take-off wheel, means biasing said carriage to align said take-off wheel and said car wheel for driving engagements, a control arm swingably attached to said car body and operative to engage said operating rod when swung beyond a predetermined position, and means interconnecting said control arm and said carriage to overcome the bias of said first means at a position short of said predetermined position to move said take-off wheel to a spaced position relative to said car wheel prior to engagement of said operating rod and said control arm.
60. A mechanism for selectively engaging a take-off wheel against the surface of a car wheel supporting a car body and to move an operating rod relative to said body, said mechanism comprising a movable carriage supporting said take-off wheel, means biasing said carriage to align said take-off wheel and said car wheel for driving engagements, a control arm swingably attached to said car body and operative to engage said operating rod when swung beyond a predetermined position, and means interconnecting said control arm and said carriage to overcome the bias of said first means at a position short of said predetermined position to move said take-off wheel to a spaced position relative to said car wheel prior to engagement of said operating rod and said control arm.
65. A mechanism for selectively engaging a take-off wheel against the surface of a car wheel supporting a car body and to move an operating rod relative to said body, said mechanism comprising a movable carriage supporting said take-off wheel, means biasing said carriage to align said take-off wheel and said car wheel for driving engagements, a control arm swingably attached to said car body and operative to engage said operating rod when swung beyond a predetermined position, and means interconnecting said control arm and said carriage to overcome the bias of said first means at a position short of said predetermined position to move said take-off wheel to a spaced position relative to said car wheel prior to engagement of said operating rod and said control arm.
70. A mechanism for selectively engaging a take-off wheel against the surface of a car wheel supporting a car body and to move an operating rod relative to said body, said mechanism comprising a movable carriage supporting said take-off wheel, means biasing said carriage to align said take-off wheel and said car wheel for driving engagements, a control arm swingably attached to said car body and operative to engage said operating rod when swung beyond a predetermined position, and means interconnecting said control arm and said carriage to overcome the bias of said first means at a position short of said predetermined position to move said take-off wheel to a spaced position relative to said car wheel prior to engagement of said operating rod and said control arm.
75. A mechanism for selectively engaging a take-off wheel against the surface of a car wheel supporting a car body and to move an operating rod relative to said body, said mechanism comprising a movable carriage supporting said take-off wheel, means biasing said carriage to align said take-off wheel and said car wheel for driving engagements, a control arm swingably attached to said car body and operative to engage said operating rod when swung beyond a predetermined position, and means interconnecting said control arm and said carriage to overcome the bias of said first means at a position short of said predetermined position to move said take-off wheel to a spaced position relative to said car wheel prior to engagement of said operating rod and said control arm.

when said control arm is swung beyond one of said positions to swing said operating lever relatively to said body, and a link arm attached to said control arm and to said carriage and operative to move said take-off wheel to a spaced position relative to said car wheel when said control arm is in said one position or beyond said one position.

5. In a car construction of the type wherein a car body defining a load-carrying chamber and a coolant chamber is supported by wheels, a fan mounted between said chambers and operative when rotated to force air circulation between said chambers, a normally closed damper mounted between said chambers and operative in the open position to define a passage for convection air circulation between said chambers, a damper operating lever attached to said car and operative when swung to predetermined position to open said damper, a carriage movably supported from the car, a take-off wheel on the carriage for selective driving engagement with one of said first wheels, a control arm swingably supported from said car body and lockable in any one of three successive positions, latch means to hold the control arm in any one of said three positions and an arm pivotally attached to said carriage and pivotally attached to said control arm and operative to position said carriage to engage said take-off wheel with said one wheel when said control arm is in one of said positions and to move said carriage to disengage said take-off wheel and said one wheel when said control arm is in the others of said positions, said control arm having a portion operative to engage said damper operating lever when in one of said other positions to open said damper.

6. In a car construction of the type wherein a car body defining a load carrying chamber and a coolant chamber is supported by wheels, a fan mounted between said chambers and operable when rotated to force air circulation between said chambers, a damper mounted between said chambers and movable to a closed position and to an open position in which it defines a passage for convection air circulation between the chambers, a take off wheel, a driving connection between the take off wheel and the fan to rotate the fan when the take off wheel is driven, a support movably carried by the car body and carrying the take off wheel for movement into and out of driving engagement with one of the first mentioned wheels, a damper operating rod connected to the damper to shift the damper between open and closed positions as the operating rod is moved, a control arm pivotally mounted on the car body, a connection between the control arm and the

support so that when the control arm is in one position the take off wheel will engage said one wheel and when the control arm is moved to a second position the take off wheel will be disengaged from said one wheel, the control arm being movable to a third position beyond the second position, and means engaged and operated by the control arm when it is moved to the third position and connected to the operating rod to shift the damper to its open position.

7. In a car construction of the type wherein a car body defining a load carrying chamber and a coolant chamber is supported by wheels, a fan mounted between said chambers and operative when rotated to force air circulation between said chambers, a damper mounted between said chambers and movable to a closed position and to an open position in which it defines a passage for convection air circulation between the chambers, a take off wheel, a driving connection between the take off wheel and the fan to rotate the fan when the take off wheel is driven, a support movably carried by the car body and carrying the take off wheel for movement into and out of driving engagement with one of the first mentioned wheels, a damper operating rod connected to the damper to shift the damper between open and closed positions as the operating rod is moved, a control arm pivotally mounted

on the car body, a connection between the control arm and the support so that when the control arm is in one position the take off wheel will engage said one wheel and when the control arm is moved to a second position the take off

wheel will be disengaged from said one wheel, the control arm being movable to a third position beyond the second position, and means engaged and operated by the control arm when it is moved to the third position and connected to the operating rod to shift the damper to its open position.
